UNITED STATES PATENT OFFICE

163,916

REFRIGERATOR CABINET

John H. Walter, Grosse Pointe, Mich., assignor
to Motor Products Corporation, Detroit, Mich.,
a corporation of New York

Application January 22, 1951, Serial No. 13,907

Term of patent 14 years

(Cl. D67—3)

To all whom it may concern:

Be it known that I, John H. Walter, a citizen of the United States of America and a resident of Grosse Pointe, in the county of Wayne and State of Michigan, have invented a new, original, and ornamental Design for a Refrigerator Cabinet, of which the following is a specification, reference being had therein to the accompanying drawing, forming a part thereof, wherein:

Figure 1 is a front elevational view of a refrigerator cabinet, embodying my new design;

Figure 2 is an elevational view thereof taken from the right hand side of the cabinet shown in Figure 1;

Figure 3 is an elevational view thereof taken

from the left hand side of the cabinet shown in Figure 1;

Figure 4 is a horizontal sectional view thereof taken on the line 4—4 of Figure 1; and

Figure 5 is a vertical sectional view thereof taken on the line 5—5 of Figure 1.

The dominant features of the design reside in the portions shown in full lines.

I claim:

The ornamental design for a refrigerator cabinet, substantially as shown and described.

JOHN H. WALTER.
